(Cl. D86—10)

To all whom it may concern:

Be it known that I, Anne Yandell, a citizen of the United States and a resident of the Borough of Manhattan, county, city, and State of New York, have invented a new, original, and ornamental Design for a Sachet or Similar Article, of which the following is a specification, reference being had to the accompanying drawing forming a part thereof.

Fig. 1 of the drawing is a top plan view of the sachet showing my new design;

Fig. 2 is a side view of the sachet showing my design; and

Fig. 3 is a bottom view of the sachet.

I claim:

The ornamental design for a sachet or similar article, as shown.

ANNE YANDELL.
